APPARATUS FOR CONDITIONING MIXTURES OF GRANULAR SOLIDS AND LIQUID FOR CENTRIFUGING

George E. Stevens, Scottsbluff, Nebr., assignor to Western States Machine Company, Salt Lake City, Utah, a corporation of Utah

Original applications April 1, 1932, Serial No. 602,621, and May 12, 1934, Serial No. 725,404. Divided and this application December 4, 1934, Serial No. 756,003

5 Claims. (Cl. 127—17)

This invention relates to apparatus for conditioning mixtures of granular solids and liquid for centrifuging, such as sugar massecuites and magmas, and is intended to solve certain problems that have long been a source of much trouble and heavy loss in the manufacture of sugar and similar materials.

For purposes of illustration the invention is described as applied to the manufacture of sugar in beet factories, although it is equally advantageous in the production of cane sugar. In the usual beet factory, after the sugar-containing juice extracted from sliced sugar beets has been subjected to boiling, filtering, and concentration 10 and crystallization in a vacuum pan, the mass of sugar grains mingled with a considerable amount of mother liquor (which mixture is termed a "massecuite") is subjected to centrifuging and washing in centrifugals of the filtering type in 15 order to obtain relatively pure sugar grains and to collect the mother liquor separately. A battery or group of several centrifugal machines is usually arranged below a common overhead mixing tank which supplies charges of massecuite to 20 the centrifugals through discharge chutes, or "goosenecks", leading from the bottom of the tank.

The centrifugally extracted syrup or mother liquor, called "green liquor", and the wash syrup 30 produced by the passage of wash water through sugar in a centrifugal are conducted to separate storage tanks, while the sugar grains retained in the centrifugal are discharged therefrom, conveyed to a "granulator" for drying, and subsequently packaged. The green liquors and wash syrups still contain a large enough sugar content 35 in solution to make its recovery a valuable and important item in sugar manufacture, and the recovery of part of this dissolved sugar constitutes what is known as the "raw side" operation 40 in sugar manufacture as distinguished from the "white side" operation briefly referred to above.

In beet sugar manufacture, centrifugally extracted liquors that hold in solution much less 45 than 60 percent of dry matter are not considered worth reprocessing and are usually sold as final molasses for cattle feed or the like. In cane sugar manufacture the liquors may be reworked 50 economically down to a dry substance content of about 40 percent. In each case when further recovery of sugar from low grade liquors is made the sugar-containing liquors or syrups are subjected to filtration, evaporation, and boiling in 55 vacuum pans until the resulting massecuite is

highly supersaturated and ready for further treatment in a "crystallizer". The object of this further treatment is to cause the greatest possible precipitation of sugar from solution into solid grains or crystals of as nearly uniform size as practicable. The crystallizers are substantially horizontal drums provided with internal stirrers through which cool water is circulated in order gradually to cool the low grade massecuite from the vacuum pan and cause additional crystals to be precipitated therefrom.

Treatment in the crystallizers is usually continued over a period of from 40 to 60 hours in order to obtain the optimum yield of sugar. It results in the production of massecuite which is very stiff and viscous due not only to the precipitation of sugar crystals but to the congelation of colloidal constituents which tend to become set or non-fluid at low temperatures.

For proper centrifuging massecuite must flow 20 readily enough to permit it to build up quickly in an even ring around the inside of the centrifugal basket and to permit proper separation of mother liquor and sugar grains. Two of the important factors affecting the fluidity of the massecuite are 25 its liquid content and its temperature. The lack of fluidity characterizing low grade massecuite from a crystallizer has always been a source of much trouble to the sugar maker. If he chills the massecuite to the low temperatures that are 30 necessary to recover the maximum amount of sugar by crystallization, a stiff and viscous mass is obtained which cannot be centrifuged satisfactorily; if he drops the massecuite from the crystallizer while still fairly hot a great deal of 35 the available crystal formation is sacrificed and to a corresponding extent sugar is left in solution and lost in the final molasses.

For many years past various attempts to solve 40 this problem have been made. Heat jacketing of the mixing tank for the purpose of circulating hot water along the bottom of the tank has been tried, but without success because the conduction of heat to the mass of material in the tank is so slow that the temperature cannot be raised substantially unless the heating fluid is hot enough to melt and redissolve and even caramelize the sugar contacting the jacketed portion of the tank, thus involving a much greater loss than gain. 45 Partial reheating of the cooled massecuite in the crystallizer by circulating hot water through the crystallizer cooling device also has been tried, but this gained no advantage—quite the contrary, in fact—because to achieve any appreciable reheat-

55

ing high temperatures must be used for a considerable period of time, and the entire mass of material must be heated, with unavoidable remelting and possibly caramelization of sugar, before the batch can be run off through the centrifugals. Moreover, this practice permits the massecuite to cool during passage from the crystallizers to the centrifugals, which may occupy a period of more than an hour for some of the charges withdrawn from the mixing tank, and cooling destroys any advantage that might have been realized from the preceding reheating operation.

Another expedient frequently tried out in prior practice is to add hot molasses or syrup to the massecuite in the mixing tank. This not only causes redissolution and melting of sugar grain but also adds heavily to the work imposed upon the centrifugals so that additional centrifugal apparatus and operators are required, thus entailing a heavy extra expense for which there is no compensating advantage. The most satisfactory expedient, and the one commonly used prior to the present invention, is to add cold water to the massecuite in the mixing tank. The cold water increases fluidity without remelting or caramelizing the sugar grains, but it redissolves a large amount of sugar and adds materially to the volume of material that must be run through the centrifugals.

The present invention solves this heretofore unsolved problem by providing improved apparatus for conditioning massecuites, magmas and like mixtures just before introduction into centrifugals,—apparatus which operates in such manner as substantially to eliminate remelting, caramelization and redissolution of the sugar grain while at the same time conditioning the material for easy and relatively quick centrifuging without increasing the volume of material to be centrifuged.

The improved apparatus in general comprises a mixing tank having in the bottom portion thereof a movable heat-transferring stirrer which is maintained at a proper temperature by the circulation of hot liquid therethrough and which is arranged to impart dry heat to a regulated stream of massecuite in an amount sufficient to render the massecuite fluent and in optimum condition for centrifuging.

The heat-transferring stirrer of the invention preferably presents effective heat-conducting surface of not less than one square foot for each cubic foot of the portion of material being stirred by it in the bottom portion of the mixing tank. In the embodiment of the invention illustrated in the drawings as the preferred form for use in the conditioning of massecuite dropped from crystallizers, the stirrer is constructed as a rotatable heating coil, with convolutions of the coil arranged to keep uniform the consistency of material adjacent thereto, and means are provided for delivering massecuite to the coil in a stream substantially equal to the flow of massecuite through the discharge chutes of the tank into the centrifugals. Thus the massecuite is continuously and uniformly conditioned and then centrifuged, until the entire supply of massecuite in the tank is exhausted.

The present application is divisional of my co-pending application, Serial No. 725,404, filed May 12, 1934, and is also divisional of my co-pending application, Serial No. 602,621, filed April 1, 1932. Subject matter shown and described but not

claimed in this application, has been claimed in the aforementioned applications.

In the accompanying drawings, which illustrate preferred embodiments of the invention for the conditioning of low grade sugar massecuites, 5

Figure 1 represents a diagrammatic side elevation of a sugar plant arrangement system including crystallizers, the improved hot minglers and centrifugals,

Figure 2, a diagrammatic end view thereof, 10

Figure 3 represents a fragmentary vertical cross sectional view of a hot mingler tank of the type diagrammatically illustrated in Figure 1,

Figure 5, a section along the line 5—5, Figure 3, 15

Figure 6, an enlarged fragmentary side view of a spiral coil of a hot mingler of the type shown in Figure 3, the coil functioning as the heating and stirring element for reducing the viscosity of the massecuite,

Figure 7, a sectional view of a modification of the tank and coil arrangement, and

Figure 8 is a section taken along the line 8—8, 20 Figure 7.

In the drawings, in the several views of which like parts have been similarly designated, the crystallizers indicated by the reference numeral 9 are shown in an elevated position and are provided with outlets 10 through which material passes by gravity into a hot mingler tank 12, the lower portion of which has convergent front and rear walls. Extending transversely of the tank 12 is a deck 13 provided with openings 14, controlled by gates 15 in operative connection with levers 16.

Extending through the tank is a hollow shaft 17 carrying a pulley 18, which may be connected with any suitable driving element (not shown) to rotate the shaft. Spiral coils 19 and 20 eccentrically placed on the shaft are in fluid-conducting connection therewith, and it will be observed that the coils are staggered as to their direction of winding, the coils 19 winding to the left, and the coils 20 winding to the right. This staggered arrangement prevents the massecuite from flowing to one end of the tank only.

Positioned inside of the coils are conduits or pipes 21 in operative connection with the source of heating fluid, these pipes functioning to increase the effective heating surface, add to the 50 agitating action of the coils as well as providing bracing elements therefor.

The circulating system for the above apparatus comprises a storage tank 23 which receives boiling water from a conveniently located boiler or other source, by means of a conduit 24. A temperature regulator 25 thermostatically adjusts a valve 26 and thereby regulates the supply of hot water to the tank 23 in accordance with a predetermined temperature of the water in the tank. The tank is provided with an overflow outlet 27.

Water from tank 23 is circulated through the heating coils 19 and 20 by means of a duplex pump 28, operatively connected with a motor 29. The water is drawn from tank 23 through a pipe 30 and then passes through a conduit 31 into the hollow shaft 17. After circulating through the coils, the water enters return conduit 32 and again enters tank 23.

In carrying out the present invention, the 70 massecuite is dropped from the crystallizers onto the deck 13 of the hot mingler tank 12, and the rate at which the massecuite passes through the openings may be regulated by adjustment of the gates 15 through the medium of levers 16. The 75

massecuite on entering the tank 12 is at once subjected to the action of the coils 19 and 20.

Since one of the dominant features of the present invention is to reduce the viscosity of the massecuite without dissolving any appreciable amount of sugar, the time during which the massecuite is subjected to the action of the moving coils, and the temperature to which the massecuite is heated must be carefully controlled.

10 The area of the moving heating surface is taken as a constant, and then the time factor is adjusted, depending upon the temperature of the massecuite entering the hot mingler tank, the density of the massecuite, the rate of movement 15 of the heat transferring surface and the temperature of the circulating medium.

The present invention departs from the prior art in providing for a relatively large heating surface, preferably a moving heating surface, for 20 contacting massecuite just before it enters a centrifugal and while it is not desired to be limited to any specific ratio of heating surface to volume of massecuite, satisfactory results are obtained by providing at least one square foot of 25 moving heating surface per cubic foot of massecuite when it is desired to have a relatively low temperature difference between the heating medium and the massecuite.

In other words, the ratio of heating surface to 30 volume of massecuite must be adjusted, together with the temperature difference so that the massecuite can pass through the hot mingler and be reheated to a suitable temperature in a relatively short time. Thus, little re-dissolving of 35 crystals is encountered, while at the same time the viscosity of the massecuite is reduced to a point where it can be readily spun in the centrifugals.

In accordance with the present invention, there 40 is employed a heating medium at a temperature only slightly higher than the final temperature of the heated massecuite. Although water is the preferred heating medium, other fluids may be used. It is of considerable importance to use a 45 moving heating surface having a temperature from 50 to 65° C. or slightly higher than the heated massecuite, since temperatures of 45° C. to 55° C. are the highest that massecuite can be reheated without dissolving an appreciable portion 50 of the sugar crystals. By the continuous contact of the moving heating surfaces and their agitation of the material, the temperature of the massecuite body being subjected to the moving surfaces can be raised a number of degrees C. in 55 a time interval of only a few minutes.

The heating coils 19 and 20 are preferably maintained at a temperature varying between 50° C. and 60° C., when the temperature of the massecuite entering the hot mingler tank 12 is about 30° C. The massecuite is then heated to a 60 temperature varying between 40° C. and 50° C., by the continuous application of dry heat.

Under the conditions above set forth, it takes approximately one and five-tenths seconds to 65 raise the temperature of one hundred pounds of massecuite 1° C., and approximately twenty-two seconds to raise one hundred pounds of massecuite 15° C., or a range of five to ten minutes to raise one ton of massecuite 15° C. The time 70 factor depends upon the temperature of the massecuite entering the tank, the density of the massecuite, the temperature of the circulating heating fluid, the rate of movement of the heating surface and the square feet of moving heating 75 surface, the latter remaining a constant.

From the foregoing, it is apparent that the massecuite is heated in a relatively short time and by a heating medium whose temperature is only slightly higher than the massecuite. The time interval required for heating is of relatively 5 short duration, and a great reduction in viscosity is effected with a consequent increase in the "raw side" capacity of the factory, while at the same time a minimum amount of crystals is re-dissolved or melted by the treatment. The agitation 10 of the material is another factor influencing the beneficial results. The material upon discharging from the hot mingler tank can be readily spun in the centrifugals, and since it is in an undiluted condition an increase of at least 15 to 15 20 per cent in centrifugal capacity results from the treatment.

The above explanation discloses that there is a correlation of three factors, namely, the time factor, the ratio of effective heating surface to 25 the volume of massecuite in the tank, and a low temperature difference between the re-heated massecuite and the heating medium.

In an actual operation, 124,360 pounds of heating fluid at a temperature of 60° C. were required 25 each hour to transmit the necessary heat to the massecuite. Stated differently, approximately 450,000 B. t. u. per hour were required to heat 30,000 pounds of low grade beet sugar massecuite 30 passing through the hot mingler tank per hour. Using water at a temperature of 60° C., 1040 B. t. u. were required per square foot of moving heating surface. 40 B. t. u. per degree difference in temperature per square foot of heating 35 surface per hour gave satisfactory results.

When the crystallizers 9 are ready to drop, the auxiliary mechanism of the system is started and the temperature regulator 25 adjusted to the desired temperature. Hot water is then circulated through the system, including the coils 19 and 20 40 until the system is well heated. The crystallizer 9 is then opened and the massecuite is allowed to flow onto the deck 13 in the hot mingler tank 12. After the deck 13 is well covered, all the gates 15 are opened a notch or two and the 45 massecuite is distributed over the coils 19 and 20. The massecuite is allowed to flow until the coils are entirely covered.

The gates 15 are then closed and all the massecuite below the deck is heated to 45°-50° C., 50 whereupon the massecuite itself becomes a heat accumulating medium. When spinning begins, the gates 15 are again opened and the inflow of massecuite is regulated to balance its discharge from the tank 12 through goosenecks 22. Thereafter, the operation is continuous. It is to be understood, however, that the apparatus is also adapted to batch treatments whenever such practice is employed.

Massecuite passing through goosenecks 22 drops 55 directly into centrifugals 33. While a gravity flow system has been illustrated, it is to be understood that the hot mingler tank is adapted for use in any type of factory arrangement, and when the crystallizers 9 are disposed at a lower 60 elevation than the centrifugals 33 and the material pumped to the centrifugals, the tank may be installed adjacent the centrifugals at any convenient point between the crystallizers and the centrifugals without impairing its efficiency.

In the modification illustrated in Figures 7 and 8, massecuite dropped from the crystallizers 9 is directed onto a chute 34 supported on the upper edge of tank 12.

A primary heating and agitating element 35 75

and a secondary heating and agitating element 36 of the system are disposed one above the other in the tank 12, which, in the operation, is a part of the secondary element.

5 The primary element comprises a tank 37, the walls of which are doubled to provide a water jacket 38. In the lower part of the tank, a shaft 39 of a rotary agitator 40 extends lengthwise thereof substantially in the axis of the circle of 10 the rounded bottom of the tank.

The shaft 39 is mounted in bearings 41 and 42, three of which are supported on cross beams 43 adjacent the ends of the tank, and one of which is at a median point of the tank, supported

15 on a cross beam 44. The portions 45 of the shaft extending through the bearings 41 and through the ends of the tank, are hollow and connected with the body part 39 of the shaft by means of flanged couplings 46.

20 Tubular stirrers 47 on the shaft, of U-shaped form, have arms 48 which project radially from the shaft in connection with its hollow end-portions 45. These rotating stirrers operate to simultaneously agitate and heat the material in 25 the tank in the manner hereinbefore described. Stuffing boxes 49 are provided at the ends of the shaft to provide a fluid-tight connection between the pipes of the fluid circulating system and the hollow portion 45 of the shaft.

30 The main parts of the U-shaped stirrers, extending parallel to the shaft, are provided with scrapers 50, to wipe the surface of the tank at the inside of its jacket, for the purpose of presenting a clean surface for the ready transference 35 of heat from the heating-fluid in the jacket to the material in the tank. The scrapers also aid in preventing any overheating of massecuite by reason of its remaining too long in contact with the water-jacketed surfaces.

40 The arms 48 are preferably arranged in pairs of unequal lengths, so that the parts of the stirrers extending parallel to the shaft, are at unequal distances from the axis of rotation of the same. In this manner, the stirring and heating 45 element covers a wide area in its rotary movement and thoroughly agitates and heats the material within said area, by the movement of the stirrers in intersecting zones.

An agitator constructed similarly to that of 50 the first described heating-element has its axis of rotation coincident with the axis of the circular bottom portion of the tank 12. The agitator, like that of the heating element 35 comprises a shaft 51, the end portions of which are 55 supported in bearings on cross beams 52.

U-shaped tubular radial stirrers 53 are connected with the hollow end portions of the shaft 51 in a circulating system of the same character as that previously described. Scrapers 54 on the 60 body parts of the stirrers, extending lengthwise of the tank, in parallel relation to the shaft, are provided to wipe the surface of the lower portion of the tank, the wall of which is doubled to provide a water jacket 55.

65 The tank 37 of the primary heating element has an overflow 56, the level of which may be varied by adjustment of a vertically movable gate 57. The gate has to this end a screw-threaded stem 58 projecting through an opening of a support 59 erected upon the edge of the tank, and it is provided with a nut 60 bearing upon the support.

It will be understood that water circulation through the water jackets 38 and 55 and through 70 75 the stirrers 47 and 53, is effected in the same

system as that disclosed in Figure 1, each of the aforementioned elements being provided with inlet and outlet connections in a manner well known in the art. The circulation of the heating fluid through the jackets and agitators is effected at 5 a predetermined and automatically regulated temperature.

Likewise, if desired, each element may be provided with its own circulating system and subject to individual temperature control. 10

When massecuite is fed from the crystallizers onto the chute 34, it enters the primary element and is at once subjected to agitation by the rotary stirrers 47.

The rotary movement of the agitator 47 keeps 15 the material in the tank 37 in motion while it is being heated by the hot water constantly circulated through the agitator and through the jacket of the tank. The scrapers 50 wipe the heating surface of the tank to constantly present 20 a clean surface. It will be understood that the temperatures of the heating mediums are only slightly higher than the temperature of the entering massecuite to avoid a harmful increase 25 in the temperature of the material.

The heated massecuite overflows from the primary tank 37 into tank 12 across the properly adjusted gate 57, and is then subjected to a second heating influence combined with an agitation action, by the heating fluid constantly circulated through agitator 53 and the jacket 55 and by the rotary movement of the agitator. The temperature of the heating mediums is preferably higher at this stage of the treatment, but only slightly in excess of the temperatures of the 35 massecuite passing through the goosenecks 22.

It is to be understood that whenever it is desired to regulate the rate of discharge from the tank, the goosenecks may be valve-controlled.

In the preferred form of the present invention, 40 there is no need to dilute the massecuite during or after crystallization, the treatment by means of moving contact with dry heat within the body of massecuite being sufficient to readily reduce the viscosity of the massecuite, even though abnormally low temperatures have been used in the crystallizer's. 45

Since there is no increase in volume and a decrease in viscosity, the centrifugals operate at maximum capacity and with an improved yield 50 of sugar per cycle, and the sugar obtained from the centrifugals may be of higher quality. These results mean substantial increases in the efficiency of sugar factory operation.

It is desired to point out that a dual action 55 is effected in the heating operation. The massecuite moves through the coils or stirrers on its way from inlet to outlet, and at the same time the coils and stirrers are moved through the massecuite. In this way a relatively large volume 60 of massecuite contacts each heating surface in a given period of time.

An example of the effectiveness of apparatus constructed in accordance with this invention in commercial operation is furnished by the following record from one of the beet sugar factories in which it has been installed. This factory during its last campaign had an average of 44 crystallizer hours for each 1150 cubic feet, or 107,000 pounds, of massecuite, during which period of 70 time the temperature of the massecuite was lowered from 60° C. to 30° C. It spun 22,379 tons of raw massecuite in 66.65 slicing days, or an average of 335.8 tons per day, or approximately 14 tons per hour. 75

After the operation of the mingler became continuous at the start of the campaign, the massecuite flowed through the gates in the deck of the mixing tank as rapidly as it was drawn off into the centrifugals. The massecuite drawn off was replaced by cold massecuite from the crystallizers, and by the time the initially cold material reached the goosenecks it had been raised from 30° C. to 44° C., in the average time of about seven 10 minutes, which was the average time of one spinning cycle of the centrifugals. Water at an average temperature of 57° C. was used to maintain the temperature of the mingler.

The average dry substance of the material 15 entering the crystallizer was 90.0, and the average dry substance leaving the crystallizer was 89.8. Small amounts of cold water were introduced into the massecuite in the crystallizers, which accounts for the fractional difference in 20 dry substance. There was no dilution of the massecuite after leaving the crystallizers, and the percentage of dry substance, or density, of the massecuite as spun was the same as when leaving the crystallizer.

25 Raw massecuite contains gums, colloids, etc., which upon cooling tend to jellify and become very viscous or semi-solid. Dry heat and agitation has the property of breaking up this viscosity and rendering the material more fluent, 30 much more so than the addition of cold water or hot syrups. For this reason, the apparatus of my invention permits the boiling of lower purity raw pans to obtain the lowest possible molasses purity, since the subsequent treatment in the 35 mixer of the resulting "tough" massecuite readily conditions it for effective treatment in the centrifugals.

It is to be understood that variations in the construction and arrangement in the elements 40 of the system and the parts of the apparatus included therein may be made within the scope of the invention. Also it is to be understood that if scrapers of the type shown in Figures 7 and 8 are desired, in a device of the type illustrated in 45 Figure 3, they may be mounted on the coils 19 and 20.

While the foregoing description has pointed out that the hot mingler is particularly adapted for the treatment of massecuite passing from the 50 crystallizers to the centrifugals, it is to be understood that the apparatus may be effectively employed in other treatments in the sugar manufacturing process and elsewhere, as at the affination station of a sugar refinery and in the conditioning of massecuites which pass from a vacuum pan to centrifugals without intermediate treatment in crystallizers.

For example, it may be used to great advantage in connection with the white mixer for controlling the temperature and viscosity of white massecuite after it is dropped from a vacuum pan and during the centrifuging of the entire batch of massecuite. As a result of such treatment a better control of the ash and moisture content in 65 the white sugar is obtained, and sugar of a more uniform quality and better color is thereby produced. The continuous, uniform high fluidity of massecuite conditioned in this manner greatly increases the capacity of the centrifugals without loss of sugar grain by dissolution, caramelization or remelting.

The foregoing data as to temperatures, etc., relate to actual operations on the raw side of a beet sugar factory. Since white cane sugar 75 massecuite, for example, is capable of with-

standing higher temperatures without injury than low grade massecuite, it will be understood by sugar engineers and operators that the temperatures used in conditioning this and other mixtures of granular solids, such as sugar, and liquids, such as syrup, may be varied in accordance with qualities of the mixture to be centrifuged.

What I claim and desire to secure by Letters Patent is:

1. In an apparatus for conditioning a mixture of sugar grains and syrup the combination of a mixer tank forming a receptacle for material to be conditioned for centrifuging, the bottom of the tank being provided with outlet discharge 15 passages for delivering the conditioned material directly to individual centrifugals, an internally heated tubular stirrer revolvably mounted in the lower portion of the tank adjacent to said delivery passages, a partition partly separating the lower portion of the tank from the upper portion thereof, controllable gates for regulating the flow of material from the upper to the lower portion of the tank, means for circulating hot fluid 20 through said stirrer, and means for maintaining the fluid circulating through the stirrer at a temperature not materially above the final temperature of the conditioned material adjacent the delivery passages, the circulating means having capacity to supply a large enough flow of hot 25 fluid to impart a uniform temperature to successive portions of the material flowing past the stirrer without substantial drop in temperature of the fluid so circulating.

2. In an apparatus for conditioning a mixture of sugar grains and syrup, the combination of a mixing tank forming a receptacle for the mixture to be conditioned and centrifuged, the bottom portion of the tank having outlet passages for delivering the conditioned material directly 40 to individual centrifugals, an internally heated tubular stirrer revolvably mounted in the lower portion of the tank adjacent said outlet passages, means for forcing a circulation of hot fluid through said stirrer while it is revolving, means 45 for maintaining the hot fluid supply at a temperature not harmfully above the maximum temperature to be imparted to the mixture near the outlet passages, the hot fluid circulating means and stirrer being dimensioned to maintain a flow 50 of hot fluid of large enough volume to transfer the required heat to the portion of the mixture being stirred without substantial drop in the temperature of the hot fluid passing through the stirrer.

3. In an apparatus for conditioning a mixture of sugar grains and syrup, the combination with a mixing tank forming a receptacle for the mixture to be conditioned and centrifuged and having bottom outlet passages for delivering the 60 conditioned material directly to individual centrifugals, an internally heated hollow stirrer revolvably mounted in the lower portion of the tank adjacent said outlet passages and acting to simultaneously stir and heat that portion of the mixture in the bottom of the tank in proximity with the stirrer, the stirrer being dimensioned to expose at least one square foot of heat-transferring surface for each cubic foot of that portion of the mixture being stirred by it at a 65 time, and means for continuously circulating through the stirrer a supply of hot fluid at a predetermined temperature not harmfully above the maximum temperature to be imparted to the mixture.

4. In a sugar centrifugal apparatus comprising a centrifugal separator and a mixing tank whose discharge outlet leads directly to the centrifugal, a partition partly dividing said tank into communicating compartments, a tubular internally heated stirrer revolubly mounted in each compartment for heating in successive stages a stream of massecuite flowing through the compartments into successive contact with the stirrers therein, means for forcing a continuous flow of hot fluid through said tubular stirrers, and means for maintaining the temperature of the hot fluid flowing through the stirrers not harmfully above the maximum temperature which it is desired to impart to the massecuite as it enters the discharge outlet.

5. Apparatus for conditioning a mixture of sugar grains and syrup for immediate centrifuging comprising, in combination, a mixing tank forming a receptacle for mixture to be condi-

tioned and centrifuged, the bottom portion of the tank having outlet passages for delivering the conditioned material directly to individual centrifugals, an internally heated tubular stirrer providing at least one square foot of heating surface for each cubic foot of mixture being stirred revolubly mounted in the lower portion of the tank adjacent said outlet passages, means for forcing a circulation of hot fluid through said stirrer while it is revolving, means for maintaining the hot fluid supply at a temperature not harmfully above the maximum temperature to be imparted to the mixture near the outlet passages, the hot fluid circulating means and stirrer being dimensioned to maintain a flow of hot fluid of large enough volume to transfer the required heat to the portion of the mixture being stirred without substantial drop in the temperature of the fluid passing through the stirrer.

GEORGE E. STEVENS. 20
